UNITED STATES PATENT OFFICE.

CORRY JONES, OF NEW YORK, N. Y.

DESIGN FOR A PINCUSHION.

SPECIFICATION forming part of Design No. 30,705, dated May 2, 1899.

Application filed April 4, 1899. Serial No. 711,741. Term of patent 7 years.

To all whom it may concern:

Be it known that I, CORRY JONES, of the city of New York, (Long Island City,) borough of Queens, in the county of Queens and State 5 of New York, have invented and produced a new and original Design for a Pincushion, of which the following is a full, clear, and exact specification.

Reference is to be had to the accompanying drawing, forming a part of this specification, in which the figure is a perspective view of a pincushion, showing my design.

The design in its entirety consists of a head

A, formed with a cap B, on the side of which appear raised annular bands C above a head 15 D, from which depends the tapering shank E.

The leading feature of the design consists of the head and the tapering shank.

I claim—

The design for a pincushion herein shown 20 and described.

CORRY JONES.
